UNITED STATES PATENT OFFICE.

MARK E. MOORE, JR., OF FAIRMONT, MINNESOTA, ASSIGNOR TO MOORE TOOL COMPANY, OF FAIRMONT, MINNESOTA, A CORPORATION OF MINNESOTA.

TAPPET-WRENCH SET.

1,404,881.

Specification of Letters Patent. Patented Jan. 31, 1922.

Application filed January 8, 1921. Serial No. 435,932.

To all whom it may concern:

Be it known that I, MARK E. MOORE, Jr., a citizen of the United States, residing at Fairmont, in the county of Martin and State 5 of Minnesota, have invented certain new and useful Improvements in Tappet-Wrench Sets, of which the following is a specification, reference being had to the accompanying drawings.

10 The valve tappets on automobile motors are very important parts, and must be adjusted properly and kept in proper adjustment, necessitating the use of a special thin wrench.

15 For a long time automobile mechanics have been in need of a set of tappet wrenches, which are capable of adjusting the tappet and lock nuts on all makes of automobiles, hence the present tappet 20 wrench set has been found to meet the need, as it will cover the entire ground.

One of the distinguishing features of a wrench of the present set is the 90 degree end, which is a distinct departure and one 25 which is desirable by automobile repair men, in that it enables the user to reach tappets easily, and which heretofore have been very difficult to hold.

A purpose of the present invention is the 30 provision of a tappet wrench set comprising a plurality of wrenches preferably eight in number, though it is obvious that the set may comprise any number of wrenches, as circumstances warrant.

35 It is a further purpose to construct each wrench from sheet steel preferably 10-gauge stock (of 9/64 of an inch), though it is obvious that any gauge material and thickness may be employed. The material 40 may be hardened to withstand the rough usage, and furthermore it is the aim to construct one end of each wrench with jaws whose sides are disposed at an angle of 22 $\frac{1}{2}$ degrees with the center line of the wrench 45 and the other end has jaws whose sides are formed at an angle of 90 degrees with the center line of the wrench. The angle of the 90 degree end may be varied 10 degrees either way.

50 It has been found that the novel feature of this wrench is the 90 degree end, as it will hold the tappets, lock nuts and set screws, which are very difficult to hold, if not impossible to hold, with a wrench whose jaws 55 are formed at an angle other than 90 degrees. The reason for this is that the 90

degree requires less working room than other wrenches.

In certain makes of automobiles the valve tappets are so close to the valve stem housing that the amount of room left for the wrench to adjust the tappets is so small that it is very difficult to adjust the tappets, with a wrench other than one of the wrenches of the present set. With the present construction of wrench any tappet on any automobile may be engaged and adjusted with no loss of time in trying to arrange the wrench into a close position.

Also a wrench of the present set is designed for adjusting lock nuts on brake bands on the rear wheels of automobiles, as there is a very small amount of room or space between the spokes of the wheels, in which to use a wrench otherwise constructed, therefore it is the aim to provide a wrench of the present character for reaching lock nuts very easily.

In certain automobiles the water pump is so placed that it interferes with the adjustment of the tappets, or it limits the amount of room for a wrench to work in, especially when adjusting the tappets on certain automobiles. The present form of wrench of the set will engage the tappets easily, and of course will decrease the amount of time used by the mechanics to finish the job.

A still further and most important purpose is the provision of a tappet wrench set, wherein a plurality of tools or wrenches 90 are embodied, and wherein the tappet engaging notch at one end of the tool body is of certain dimensions, while the other tappet engaging notch or recess or opening is of slightly increased dimensions; while the adjacent tool or wrench has its end corresponding to the first mentioned wrench end provided with a notch or tappet engaging recess of dimensions corresponding to the dimensions of the notch last mentioned, so that the wrench set may be employed for adjusting the various tappets on all makes of 95 automobiles.

While the design and construction at present illustrated and set forth is deemed preferable, it is obvious that as a result of a reduction of the invention to a more practical form for commercial purposes, the invention may be susceptible of changes, and the right to these changes is claimed, provided they 100 are comprehended within the scope of what is claimed.

The invention comprises further features and combination of parts, as will be herein-after set forth, shown in the drawings and claimed.

5 In the drawings:—

Figure 1 is a view in perspective of a holder constructed of any suitable material preferably canvas, duck or any other material with spaces formed therein for the reception of a tappet wrench set.

Figure 2 is a plan view of a wrench with a $1/2$ inch opening at one end and a $5/8$ inch opening at the other end.

Figure 3 is a plan view of a tappet wrench 15 with a $9/16$ and a $1/2$ inch opening at its opposite ends, the former being on a $22\frac{1}{2}$ degree end opposite to the end of the first wrench.

Figure 4 is a plan view of a tappet wrench 20 with a $5/8$ inch opening on the $22\frac{1}{2}$ degree end and the $11/16$ inch opening on the 90 degree end.

Figure 5 is a view of a tappet wrench 25 with openings at its opposite ends, one measuring $11/16$ inch on the $22\frac{1}{2}$ degree end, the other measuring $9/16$ of an inch on the 90 degree end.

Figure 6 is a plan view of a tappet wrench 30 with a $3/4$ of an inch opening on the $22\frac{1}{2}$ degree end and a $7/8$ opening on the 90 degree end.

Figure 7 is a plan view of a tappet wrench 35 provided with openings of different sizes, one at the $22\frac{1}{2}$ degree end measuring $13/16$ of an inch, the other measuring one inch.

Figure 8 is a plan view of a tappet wrench 40 with openings respectively of its opposite ends, one on the $22\frac{1}{2}$ degree end measuring $7/8$ of an inch, the other on a 90 degree end measuring $3/4$ inch.

Figure 9 is a plan view of a tappet wrench 45 having a one inch opening on the $22\frac{1}{2}$ degree end with a $13/16$ inch opening on the 90 degree end.

45 Referring more especially to the drawings, 1 designates a holder constructed of any suitable material preferably canvas or duck, said holder having a plurality of spaces or compartments for the reception 50 of the wrenches, there being a cover or closure 2.

Each wrench, though it may be made of any material preferably metal of any thickness, it is designed to be made of steel, from 55 10-gauge stock, preferably $9/64$ of an inch in thickness, and is hardened to withstand rough usage.

The opposite ends of each wrench body 4 are provided with enlargements 5 and 6. 60 The enlargement 5 is provided with wrench jaws 7 causing to be formed an opening or recess 8 for engagement with various tappets or lock nuts on automobiles. The opposite edges of the jaws 7, though they may be disposed at any angle, are preferably disposed

on an angle of $22\frac{1}{2}$ degrees. The enlargement 6 of the other end is provided with jaws 9, which are spaced in parallelism, causing to be formed a recess or opening 10. The opposite edges of these jaws 9 are preferably disposed on an angle of 90 degrees relatively to the shank of the tool or wrench, enabling the jaws to readily reach tappets or lock nuts, which heretofore have been found difficult to reach with the ordinary wrench. It is obvious that these edges of the jaws may be varied 10 degrees either way relatively to the 90 degrees, and it has been found that where the jaws 7 would not conveniently reach certain tappets or lock nuts, the jaws 9 would, and vice versa. It will be noted that these openings or recesses of the various wrenches are of different dimensions. For instance the opening or recess 8 may be of one-half inch measurement 85 from the points indicated at *a*, while the recess or opening 10 may be of a measurement of $5/8$ of an inch, while the opening of the adjacent wrench corresponding to the opening 8 may be of a measurement of $5/8$ of an inch, and the opening at the opposite end of the adjacent wrench preferably $11/16$ of an inch, and so on $3/4$ of an inch, $13/16$ of an inch, and $7/8$ of an inch, thereby providing a set of wrenches or tools, wherein 90 no one wrench is provided with two openings of the same dimensions, and furthermore it will be found that the half inch openings are disposed on a $22\frac{1}{2}$ degree angle end, while the opening of $9/16$ is disposed 100 on a 90 degree angle end, while the $5/8$ inch openings may be found on the $22\frac{1}{2}$ degree angle end of the second wrench, and the $11/16$ inch openings on the 90 degree angle end of the second wrench and vice versa. 105 In other words the different openings may be varied, and furthermore no two openings are the same on any one wrench.

The invention having been set forth, what is claimed as being useful is:—

As a new article of manufacture, a tappet wrench set comprising a plurality of wrenches, each having jaws at one end disposed substantially at an angle of ninety degrees, and jaws at its opposite end at an angle of substantially twenty-two and a half degrees, the openings bounded by both degree jaws gradually increasing in size throughout the set, the openings between the ninety degree jaws being substantially the same as those, which are between the twenty-two and a half degree jaws but advanced in location on a wrench ahead throughout the successive wrenches of the set, whereby no two openings are the same on any one wrench, thereby making it possible to adjust the tappets and lock nuts of the same size.

In testimony whereof I hereunto affix my signature.

MARK E. MOORE, JR.
